UNITED STATES PATENT OFFICE.

PIERRE E. HAYNES AND HAROLD E. THOMPSON, OF BUFFALO, NEW YORK, ASSIGNEES
TO THE LINDE AIR PRODUCTS COMPANY, OF CLEVELAND, OHIO, A CORPORATION
OF OHIO.

EXPLOSIVE.

1,282,229.

No Drawing.

Specification of Letters Patent. Patented Oct. 22, 1918.

Application filed March 8, 1918. Serial No. 221,305.

To all whom it may concern:

Be it known that we, PIERRE E. HAYNES and HAROLD E. THOMPSON, both citizens of the United States, residing at Buffalo, 5 county of Erie, and State of New York, have invented certain new and useful Improvements in Explosives, of which the following is a full, clear, and exact description.

10 This invention relates to explosive compounds or mixtures of the type in which a combustible substance, preferably a solid carbon-compound, is impregnated or mixed with a liquefied gas capable of supporting the combustion of said substance. Its chief 15 object is to provide a powerful explosive of this class, which shall be safe to handle and relatively inexpensive to manufacture. To this and other ends the invention consists 20 in the novel mixture, compound, or composition of matter hereinafter described.

Heretofore, in explosives of the class indicated, lamp black, charcoal, asphalt, paraffin and like materials have been used as 25 combustible ingredients, with liquid oxygen as the combustion-supporting agent. In order that more oxygen may be absorbed it has been proposed to mix more or less kieselguhr with the combustible, but as kieselguhr 30 is inert, that is, incombustible, its presence on the whole is not always beneficial. In fact it may actually diminish the force of the explosion.

In our composition we use liquid oxygen, 35 or liquid ozone, or a mixture of the two as the oxidizing or combustion-supporting agent, and the oxidizable or combustible ingredient is preferably wood, cellulose, charcoal or carbon obtained from trees, bushes, 40 etc., of the ochroma family, preferably *Ochroma lagopus*, vulgarly known as the balsa tree. The wood is preferably ground, shredded, cut or otherwise disintegrated to suitable fineness, and dried; and may, if 45 desired, be in the form of charcoal. The material so obtained is made up into cartridges and when immersed in liquid air, oxygen or ozone or any mixture thereof, is completely and uniformly saturated. Upon withdrawal 50 from the liquid, superficial evaporation ensues, and the liquid evaporated from the inner surface is replaced by liquid from the inner

portions so that substantial uniformity of impregnation is maintained.

Among the advantages that we have 55 found in the use of balsa wood in some form is its remarkable absorptive power, being capable of taking up a far greater quantity of the oxidizing liquid than are the combustibles mentioned above as hitherto employed in explosives of this class. Moreover, finely divided balsa wood or fiber may be used without other preliminary treatment than the removal of water, though we prefer that it be thoroughly carbonized. 60

We have found that liquid ozone, and mixtures of liquid ozone and liquid oxygen, do not react spontaneously with certain hydrocarbon compounds, such as paraffin, and that a cartridge containing such substances, 70 with kieselguhr or other absorbent, possesses greater explosive energy than a cartridge of the same volume using liquid oxygen instead of or without liquid ozone. Furthermore, liquid ozone has a density almost fifty 75 per cent. greater than liquid oxygen and hence represents a correspondingly greater concentration of gaseous oxygen. It also has the peculiar characteristic of combining with the combustible more rapidly and more 80 violently than does liquid oxygen. And its boiling point being considerably higher than that of liquid oxygen it evaporates less rapidly than the latter in a mixture containing the two. Hence loss from such a mixture 85 by evaporation tends to a concentration of ozone, the more valuable of the two ingredients.

It is to be understood that the invention is not limited to the specific composition 90 herein described, but can be embodied in other mixtures without departure from its spirit.

We claim:

1. A composition of matter for use as an 95 explosive, containing balsa wood as a combustible and one or more liquefied gases capable of oxidizing the combustible, as set forth.

2. A composition of matter for use as an 100 explosive, containing carbonized balsa wood as a combustible and one or more liquefied gases capable of oxidizing the combustible.

3. A composition of matter for use as an

explosive, containing balsa wood and liquid ozone.

4. A composition of matter for use as an explosive, containing a combustible and liquid ozone.

5. A new composition of matter for use

as an explosive, containing carbonized balsa wood and liquid ozone.

In testimony whereof we hereunto affix our signatures.

PIERRE E. HAYNES.
HAROLD E. THOMPSON.
